(57) **CLAIM**

The ornamental design for a baby crib liner, shown and
described.

DESCRIPTION

FIG. 1 is a perspective view showing the open top and four
walls of the liner;

FIG. 2 is a side elevational view of the openable side wall;
FIG. 3 is an end elevational view of one of the two identical
end walls;

FIG. 4 is a bottom plan view showing the bottom wall; and,
FIG. 5 is a top plan view showing a top of each wall and the
integral bottom wall.
